UNITED STATES PATENT OFFICE

JAMES SHAW, OF PATERSON, NEW JERSEY

TENSION DEVICE FOR AUTOMATIC LOOM SHUTTLES

Application filed September 19, 1928. Serial No. 306,943.

This invention relates to a tensioning device for loom shuttles which are designed and adapted to receive full quills and from which the empty quills are ejected automatically in the operation of the loom.

The principal object of the invention is the provision of a device applied to a shuttle body which is designed and adapted to keep the quill thread under the proper tension, and to release the thread of the quill when the latter is ejected from its holding means by another full quill which is automatically inserted into the shuttle body, the thread of the latter quill being automatically placed under tension, and threaded to the shuttle body in the usual movements thereof.

With the foregoing and other objects in view the invention resides in the improved combination, particular construction, arrangement and operation of the parts hereinafter fully described and illustrated in the accompanying drawings, in which—

Figure 1 is a plan view of a shuttle with a quill therein, and the tensioning device of the present invention applied to the body of the shuttle, the parts being shown in the normal relationship.

Fig. 2 is an enlarged side view, partly in section, and portions being broken out, with the parts shown in the normal relationship.

Fig. 3 is an enlarged plan view of one end of the shuttle, showing the relative disposition of the parts when threading the shuttle.

Fig. 4 is a sectional view taken on the line 4—4 of Fig. 3.

Referring now more particularly to the several views of the drawings, it will be apparent that, there is shown a shuttle body 10 which is provided with holding means 11 at one end designed and adapted to receive a quill 12, to hold the quill endwise therein in thread delivering position, and from which the empty quill may be ejected by the pressure of another full quill automatically inserted in the holding means 11 of the shuttle body. The shuttle body 10 is provided with a thread groove 13, and a thread outlet hole 14 with pins 15. A box 16 is arranged and securely held in the shuttle body 10 and is positioned with respect to the groove 13 and

hole 14. Tension members 17 are positioned on the shuttle body 10 in cooperative relationship. Each tension member 17 is produced from a single piece of material to provide an eye 18 at one end, a coil 19, and spaced thread engaging hooks 20 which also serve as guides. Each tension member 17 is mounted for pivotal movement and this is accomplished by the employment of a pivot or fulcrum screw or other suitable element 21 carried by the shuttle body 10. Each tension member 17 has an inwardly bowed portion 22 for a purpose to appear. The hooks 20 of the tension members 17 are disposed in the box 16 and bear such relationship to each other as to cooperate when moved on their pivots or fulcrums 21 to engage the quill thread and zigzag the same as shown in Fig. 1 to keep the thread under the proper tension. Each tension member 17 is under the influence of an elastic member 23 in the form of a rubber band, one end of which is connected with the eye 18 of the related tension member 17 and the opposite end thereof is wrapped around a tension screw 24 carried by the shuttle body 10. The elastic members 23 serve for the purpose of urging the tension member 17 to the positions in which they place the quill thread under tension.

In order to effect the movement of the tension members 17 to release the thread of the quill when substantially empty, and when the latter is being ejected from the holding means 11 by another full quill which is being substituted for the empty quill in the movement of the shuttle and the operation of other appurtenances of the loom for this purpose, there is provided means presently to be described. A combined latch and cam element 25 is mounted for pivotal movement on a pin 26 extending transversely of the shuttle body 10. The element 25 is provided with cams 27 and is also provided with a notch 28. The element 25 is under the influence of a flat spring 29, one end of which is secured as at 30 to the shuttle body 10, and the opposite end is constantly in contact with the element 25. The spring 29 has a normal tendency to urge the element 25 to a position to latch the tension members 17 against movement which

would permit the hooks 20 to release the quill thread under normal conditions. The element 25 also serves for the purpose of actuating the tension members 17 to release the quill thread in a manner to be explained.

5 Referring now to Fig. 1 it will be apparent that the parts are in the normal relationship in which the quill thread is maintained under the proper tension and is threaded through the outlet hole 14. When the quill inserted 10 in the shuttle body is substantially empty, there comes a time in the operation of the loom when another full quill is automatically delivered to the shuttle body, and presses 15 out the empty one, which on its way out of the shuttle body engages the element 25 causing the same to move on its pivot. This movement of the element 25 causes the cams 27 thereof to act on the bowed portions 22 of the tension members 17, causing the latter to be moved to relative positions in which their hooks 20 disengage the thread of the substantially empty outgoing quill, as shown most clearly in Fig. 3. It will be apparent that the element 25 is moved against the action of 20 spring 29 which functions immediately after the outgoing quill is fully ejected, to bring the element 25 to its normal position. This allows the elastic members or rubber bands 25 23 to come into play to move the tension members 17 to relative positions in which their hooks 20 will engage the thread of the incoming full quill, and in the movement of the shuttle the thread will be automatically 30 passed through the outlet hole 14 thereby 35 properly threading the shuttle as well as placing the thread of the quill under the proper tension. It will be apparent that by providing the notch 28 in the element 25 the latter will not interfere with the thread. It 40 will also be apparent that the screws 24 may be adjusted or rotated in order to vary the tension of the elastic members 23.

It is to be understood that the invention is 45 not restricted to the precise arrangement of parts shown and described, as details of construction may be modified and rearranged without departing from the spirit of the invention, the scope of which is limited only by the terms of the appended claims.

I claim:

1. A tensioning device for an automatic loom shuttle, comprising the combination with a shuttle body provided with means for releasably holding a quill, of pivotally mounted members on the shuttle body, said members being provided with coacting thread engaging portions, means acting on said members and having a normal tendency to keep them under tension while their thread engaging portions are engaged, and means carried by the shuttle body adapted to be operated by the quill when the latter is being ejected from the holding means, to effect the pivotal movement of said members, for the

purpose of disengaging said thread engaging portions from the thread.

2. A tensioning device for an automatic loom shuttle, comprising the combination with a shuttle body provided with means for releasably holding a quill, of thread tensioning means carried by said shuttle body, and a spring actuated cam member pivotally connected with said shuttle body adapted to be operated by the quill when the latter is being ejected from the holding means, to actuate said tensioning means, for the purpose of disengaging the tensioning means from the thread.

3. A tensioning device for an automatic loom shuttle, comprising the combination with a shuttle body provided with means for releasably holding a quill, of thread engaging members, tensioning means acting on said members to keep them under tension, means carried by said shuttle body adapted to be operated by a quill when the latter is being ejected from said holding means, to cause the actuation of said members, for the purpose of releasing the thread, and means acting on the last mentioned means and having a normal tendency to urge the latter to a normal position, to allow said members to occupy their thread engaging positions.

4. A tensioning device for an automatic loom shuttle, comprising the combination with a shuttle body provided with means for releasably holding a quill, of thread tensioning means carried by said body to tension the quill thread, and a latch carried by the shuttle body adapted to be operated by the quill when the latter is being ejected from the holding means for the purpose of disengaging said tensioning means from the thread, said latch being automatically operable to allow the tensioning means to return to normal thread tensioning relation when the quill has been ejected, and also serving to prevent the tensioning means from disengaging itself from the thread.

5. A tensioning device for an automatic loom shuttle, comprising the combination with a shuttle body provided with means for releasably holding a quill, of thread tensioning means carried by said body to tension the quill thread, and means carried by said body adapted to be operated by the quill when the latter is being ejected from the holding means for the purpose of disengaging said tensioning means from the thread, said last mentioned means being automatically operable to allow the tensioning means to return to normal thread tensioning relation when the quill has been ejected, and also serving to prevent the tensioning means from disengaging itself from the thread.

JAMES SHAW.
